US00D987818S

(12) **United States Design Patent** (10) **Patent No.:** **US D987,818 S**
(45) **Date of Patent:** **** May 30, 2023**

(54) **SYRINGE ADAPTOR**

(71) Applicants: **Bobby Nourani**, Irvine, CA (US);
Michael Stephen Rafferty, Madison,
WI (US)

(72) Inventors: **Bobby Nourani**, Irvine, CA (US);
Michael Stephen Rafferty, Madison,
WI (US)

(73) Assignee: **Bobby Nourani**, Long Beach, CA (US)

(**) Term: **15 Years**

(21) Appl. No.: **29/715,817**

(22) Filed: **Dec. 4, 2019**

(51) LOC (14) Cl. **24-02**

(52) U.S. Cl.

USPC **D24/130**

Primary Examiner — Nathan M Johnston

(57) **CLAIM**

The ornamental design for a syringe adaptor, substantially as shown and described.

DESCRIPTION

FIG. 1 is a front perspective view of the first embodiment of the syringe adaptor showing our new design;
FIG. 2 is a rear perspective view thereof;
FIG. 3 is a front perspective view of the second embodiment of the syringe adaptor showing our new design;
FIG. 4 is a rear perspective view thereof;
FIG. 5 is a perspective view of the third embodiment of the syringe adaptor showing our new design;
FIG. 6 is an additional perspective view thereof;
FIG. 7 is a perspective view of the forth embodiment of the syringe adaptor showing our new design;
FIG. 8 is an additional perspective view thereof;
FIG. 9 is a front elevational view of the fifth embodiment of the syringe adaptor showing our new design;
FIG. 10 is a rear elevation elevational view thereof;
FIG. 11 is a left side elevational view thereof;
FIG. 12 is a right side elevational view thereof;
FIG. 13 is a top plan view thereof; and,
FIG. 14 is a bottom plan view thereof.
